(57) **CLAIM**

The ornamental design for a “handle magnet,” as shown and described.

DESCRIPTION

FIG. 1 is a side elevational view of the handle magnet, the left elevational view being a mirror image thereof;

FIG. 2 is a front view of the handle magnet shown in FIG. 1;

FIG. 3 is a rear view of the handle magnet shown in FIG. 1; FIG. 4 is a plan view of the handle magnet shown in FIG. 1; and,

FIG. 5 is a bottom view of the handle magnet shown FIG. 1.

The ribs shown in phantom lines in FIGS. 1-5 are for illustrative purposes only and form no part of the claimed design.
